(57) **CLAIM**

The ornamental design for a set of recovery boards including base plate, as shown and described.

DESCRIPTION

FIG. 1 is a front view of a set of recovery boards including base plate showing our new design;

FIG. 2 is a rear view, thereof;

FIG. 3 is a side view, thereof;

FIG. 4 is a side view of two stacked set of recovery boards including base plates;

FIG. 5 is a top view of a set of recovery boards including base plate;

FIG. 6 is a front top perspective view, thereof;

FIG. 7 is a rear top perspective view, thereof;

FIG. 8 is a front top perspective view of a set of recovery boards including base plate with an enlarged view of a cleat portion of the set of recovery boards including base plate;

FIG. 9 is a front top perspective view of two stacked set of recovery boards including base plates;

FIG. 10 is a rear top perspective view of a recovery board with an attached base plate, and an enlarged view of a portion of the base plate;

FIG. 11 is a top perspective view of two recovery boards joined with a base plate;

FIG. 12 is a bottom perspective view of a set of recovery boards including base plate; and,

FIG. 13 is a bottom perspective view of a recovery board including a base plate.
